GAS-OPERATED SELF-LOADING FIREARM

Carl G. Swebilius, Hamden, Conn.

Application March 5, 1943, Serial No. 478,058

11 Claims. (Cl. 42—3)

The present invention relates to improvements in gas-operated self-loading firearms, i. e., firearms in which the energy developed by the discharge of one cartridge effects the extraction and ejection of the said cartridge preparatory to the insertion of a fresh cartridge. More particularly, the present invention relates to means for operatively interconnecting the piston and breech-bolt of a firearm of the type referred to.

One of the objects of the present invention is to provide a gas-operated self-loading firearm in which superior means is provided for operatively interconnecting the piston and the breech-bolt.

Another object of the present invention is to provide superior means for operatively interconnecting the piston and breech-bolt of a gas-operated self-loading firearm in such manner that the said means may be readily disconnected from the structure to permit inspection, repair and replacement.

A further object of the present invention is to provide superior means for operatively interconnecting the breech-bolt and piston of a gas-operated self-loading firearm, which means is characterized by reliability and effectiveness of operation, combined with capacity for convenient disassembly.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1a is a broken view partly in side elevation and partly in vertical central-longitudinal section of the intermediate portion of a firearm-structure embodying the present invention;

Fig. 1b is a similar view of the portion of the firearm immediately forward of the portions shown in Fig. 1a;

Fig. 2 is a transverse sectional view taken on the line 2—2 of Fig. 1b;

Fig. 3 is a similar view taken on the line 3—3 of Fig. 1b;

Fig. 4 is a broken longitudinal sectional view taken on the line 4—4 of Fig. 2;

Fig. 5 is a broken longitudinal sectional view taken on the line 5—5 of Fig. 1a;

Fig. 6 is a transverse sectional view taken on the line 6—6 of Fig. 1a;

Fig. 7 is an inner face view of the action-slide, detached;

Fig. 8 is a view in side elevation of the connecting-link, detached;

Fig. 9 is a view in side elevation of the cylinder-fitting, together with the portion of the barrel adjacent thereto;

Fig. 10 is a perspective view of the piston, detached;

Fig. 11 is a view corresponding to Fig. 4 but showing the connecting-link in the position which it assumes during its attachment to or detachment from the piston;

Fig. 12 is a perspective view of the spring-retaining unit, detached; and

Fig. 13 is a broken longitudinal sectional view of the same nature as Fig. 4 but showing a modified construction of the connecting-link and piston.

The structure of Figs. 1 to 12 inclusive

20 The gas-operated self-loading firearm chosen for purposes of illustrating one embodiment of the present invention in the figures referred to, includes in the main a frame 15, a receiver 16, a barrel 17, a stock 18 and a barrel-cover 19. The firearm also includes a breech-bolt 20, an action-slide 21, a connecting-link 22, a reciprocating-piston 23 and a cylinder-fitting 24.

The stock 18 and barrel-cover 19 above referred to are preferably formed of wood or other suitable heat-insulating and shock-absorbing material, while the remaining parts above described are preferably formed of high-grade steel.

The frame 15 is mainly of plate-like form and is formed on its lower edge with a loop-like trigger-guard 25 extending around a trigger 26 which controls the firing mechanism of the firearm in any suitable manner not requiring detailed description herein.

40 The frame 15 is rigidly secured to the stock 18 in any suitable manner such, for instance, as by a bolt 27, while the said frame 15 and receiver 16 are detachably secured together in any suitable manner not requiring detailed description herein, so that in effect the two said elements may be said to constitute a frame-structure. The barrel 17 is rigidly coupled at its rear end with the forward end of the receiver 16, which latter is generally of cylindrical form exteriorly and is pro-

50 vided in its interior with an axial passage 28 in which the breech-bolt 20 both reciprocates and oscillates. The rear end of the passage 28 just referred to is closed by a standing-breech 29 forming part of the upper rear portion of the frame 15.

At its forward end, the breech-bolt 20 is provided with a laterally-projecting lug 30 normally located (when the breech-bolt is in its breech-closing position) in a locking-notch 31 formed in the side-wall of the receiver 20 and leading downwardly from the forward end of a longitudinal clearance-slot 32 also formed in the right side of the receiver 20 and providing for the longitudinal movement of the lug 30 of the breech-bolt 20. Intersecting the upper side of the clearance-slot 32 slightly forwardly of midway of the length thereof, is an ejection-opening 33 through which the cases of fired cartridges may be ejected in any convenient manner not requiring detailed description herein.

The outer end of the lug 30 of the breech-bolt 20 projects into a cam-recess 34 formed in the inner face of the action-slide 21 and acting on the said lug 30 to both turn the same to unlock and lock the breech-bolt and to reciprocate the said breech-bolt in a manner well understood in the art and broadly similar to the manner in which the breech-bolt of the well-known Garand military rifle is operated.

The inner face of the action-slide 21 is cylindrically contoured to correspond to the exterior contour of the adjacent portion of the receiver 16 upon which the said action-slide reciprocates in a direction lengthwise of the firearm-structure.

The action-slide 21 is preferably formed of two major parts for purposes of economy, namely, a sheet-metal shell 35 of circular arc form in cross section and a relatively-heavy body 36 brazed or otherwise rigidly united to the outer surface of the said shell 35. Adjacent its rear end and hence about midway the length of the action-slide 21, the body 36 of the said action-slide is provided with an outwardly-projecting operating-handle 37 by means of which the said action-slide and hence the breech-bolt 20 may be manually operated when desired.

About midway of its length, the action-slide 21 is formed with a downwardly-and-inwardly-opening recess 38 which receives a coupling-lug 39 projecting inwardly from the rear end of the connecting-link 22 before referred to. Adjacent and intersecting its recess 38, the action-slide 21 is formed with a horizontal slot 40 which also intersects the exterior periphery of the said action-slide both to the front and to the rear of the operating-handle 37.

Mounted about midway of its length in the horizontal slot 40 in the action-slide 21 is a coupling-lever 41 swinging upon a pivot-pin 42 mounted vertically in the base portion of the operating-handle 37 of the action-slide 21, as is clearly shown in Figs. 5, 6 and 7. At its forward end, the coupling-lever 41 is provided with a substantially-semicircular coupling-nose 43 normally entered into a coupling-recess 44 formed in the outer face of the coupling-lug 39 of the connecting-link 22. The rear end of the coupling-lever 41 is broadened laterally to provide a convenient finger-piece and is located immediately to the rear of the operating-handle 37 of the action-slide 21. A helical spring 45 is interposed between the rear end of the coupling-lever 41 and the rear end of the action-slide 21 in position to exert a yielding force in a direction to turn the said coupling-lever 41 in a counterclockwise direction as viewed in Fig. 5 and hence to yieldingly maintain its coupling-nose 43 in the coupling-recess 44 of the action-slide 21. The coupling-lever 41 thus serves to releasably hold the

rear end of the connecting-link 22 in coupled relationship with respect to the action-slide 21.

For the purpose of guiding the reciprocating movement of the action-slide 21 on the receiver 16, the said action-slide has the respective opposite side-edges of its sheet-metal shell 35 bent substantially radially inwardly to provide two parallel longitudinal guide-flanges 46 and 47 respectively. In line with each of the guide-flanges 46 and 47 just referred to, the receiver 16 is formed on its outer surface with one of two parallel guide-grooves 48 and 49 respectively receiving with a sliding fit the guide-flanges 46 and 47, as is especially well shown in Fig. 6. At their respective forward ends, the guide-grooves 48 and 49 just referred to intersect the forward end of the receiver 16, so that the action-slide 21 may be conveniently removed and installed.

Returning now to the cylinder-fitting 24 before referred to, it will be noted by reference to Figs. 1b, 3 and 9 in particular, that the said fitting includes a body-portion 50, the upper portion of which is formed with a cylindrically-contoured passage 51 extending longitudinally therethrough from end to end and snugly fitting a similarly-contoured portion 52 of the barrel 17. The body-portion 50 of the cylinder-fitting 24 also extends below the adjacent portion of the barrel 17 and in its lower portion is provided with a longitudinal rearwardly-opening piston-chamber 53 having its forward end sealed by a closure-screw 54. Vertically intermediate its cylindrical passage 51 and the piston-chamber 53, the body-portion 50 has an anchoring-pin 55 extending transversely therethrough and through the lower part of the portion 52 of the barrel 17.

The cylinder-fitting 24 also includes a tubular extension 56 rigid with and projecting rearwardly from the lower part of the body-portion 50 and having an internal bore 57 arranged coaxially with respect to the piston-chamber 53. Adjacent the forward end of the connecting-link 22, the cylinder-fitting 24 is formed with a longitudinal clearance-slot 58 extending rearwardly from the body-portion 50 to a point closely approaching the rear end of the extension 56, as is clearly shown in Fig. 9.

For the purpose of conducting gas under pressure into the piston-chamber 53 of the cylinder-fitting 24 from the bore 59 of the barrel 17, the said barrel is formed with a vertical gas-passage 60 leading downwardly from the said bore 59 to the underside of the portion 52. The lower end of the gas-passage 60 just referred to communicates with the upper end of a gas-passage 61 formed in the body-portion 50 of the cylinder-fitting 24. At its lower end, the gas-passage 61 communicates with the forward portion of the piston-chamber 53 at a point immediately rearwardly of the closure-screw 54.

Reciprocating partly in the piston-chamber 53 and partly in the bore 57 of the cylinder-fitting 24, is the piston 23 before referred to. The forward portion of the said piston 23 is smaller in diameter than its rear portion, and at its extreme forward end is formed with a piston-head 62 having a close sliding fit in the piston-chamber 53. The rear portion of the piston 23 is sized to have a smooth sliding fit with respect to the surfaces of the bore 57 in the cylinder-fitting 24. The rear portion of the piston 23 is also provided with a rearwardly-opening cylindrically-contoured socket 64 into which extends the forward end of a helical breech-closing spring 65.

Starting at a point slightly to the rear of the

front wall 66 of the socket 64 in the piston 23 and extending rearwardly, is a clearance-slot 67 located circumferentially in line with the longitudinal clearance-slot 58 in the cylinder-fitting 24. Extending diagonally downward and inwardly from the forward end of the coupling-link 22, is an integral front coupling-lug 68 which passes through both the clearance-slot 58 in the cylinder-fitting 24 and through the clearance-slot 67 in the piston 23 and into the socket 64 in the latter, as is especially well shown in Figs. 2 and 4. The coupling-lug 68 includes a forwardly-extending coupling-finger 69 having its respective upper and lower edges cylindrically-contoured and loosely fitting the forward portion of the socket 64 in the piston 23, as is best shown in Fig. 4. The front coupling-lug 68 is also formed with a short rearwardly-extending locking-finger 70 fitting within the forward end of the breech-closing spring 65.

As thus constructed and arranged, the breech-closing spring 65 thrusts forwardly upon the front coupling-lug 68 of the connecting-link 22 and serves to yieldingly urge the said connecting-link, the piston 23, the action-slide 21 and the breech-bolt 20 into their respective forward positions. By fitting over the locking-finger 10 of the front coupling-lug 68, the forward end of the breech-closing spring 65 serves to positively restrain the said coupling-lug from being removed radially outwardly from within the socket 64 in the piston 23 until the said spring is first removed in a manner as will be later described herein. Normally, the upper surface of the coupling-finger 69 of the front coupling-lug 68 positively acts to restrain the radial movement referred to and receives on its forward face the thrust from the front wall 66 of the socket 64 of the piston 23 when the said piston is moved rearwardly by gas pressure in a manner as will hereinafter appear.

The rear portion of the breech-closing spring 65 encircles a spring-guiding rod 71 rigidly secured to and extending forwardly from the depending-arm of a substantially-Z-shaped bracket 72 removably mounted against the under face of the receiver 16, as is shown in Fig. 1a. At its forward end, the bracket 72 is reversely bent to provide an integral upwardly-and-rearwardly-inclined coupling-finger 73 fitting into a similarly-inclined coupling-recess or socket 74 formed in the lower forward corner of the receiver 16, as shown in Fig. 1a. Immediately forwardly of the point of its securement to the bracket 72, the rear end of the spring-guiding rod 71 is formed with an annular collar 75 receiving on its forward face the rearward thrust of the breech-closing spring 65. The tension of the breech-closing spring 65 normally holds the coupling-finger 73 of the bracket 72 in the coupling-recess 74 of the receiver 16.

When the firearm is discharged, gas pressure from the bore 59 of the barrel 17 will pass downwardly through the gas-passages 60 and 61 into the forward end of the piston-chamber 53. This gas will act on the forward end of the piston-head 62 of the piston 23 to drive the said piston violently rearwardly. The rearward movement of the piston 23 will be transmitted to the front coupling-lug 68 of the connecting-link 22 by the engagement of the front wall 66 of the socket 64 in the said piston with the forward end of the coupling-finger 69. Thus, the connecting-link 22 will be driven rearwardly, and through the intermediary of its rear coupling-lug 39 and the

rear wall of the recess 38 in the action-slide 21, the said action-slide will be also moved rearwardly.

The rearward movement imparted to the action-slide 21 as above described, will cause the said action-slide to act through the intermediary of its cam-recess 34 and the lug 36 on the forward end of the breech-bolt 20, to turn and rearwardly retire the said breech-bolt and thus effect the extraction and ejection of the just-fired cartridge. The rearward movement of the parts as just above described will be limited by the engagement of the rear face of a stop-finger 76 formed on the connecting-link 22 with the forward face of a collar 77 mounted on the barrel 17 immediately forwardly of the receiver 16.

The rearward movement of the parts as above described under the impulse supplied by gas pressure of the just-fired cartridge will occur against the counterurge of the breech-closing spring 65. Normally, all of the parts referred to which have just completed their respective rearward movements, will immediately return to their forward positions under the urge of the breech-closing spring 65 immediately following the checking of the rearward movement of the parts as described. This return or forward movement of the parts will cause the breech-bolt to insert a fresh cartridge into the cartridge-chamber of the firearm in a suitable manner well understood in the art, preparatory to another cycle of operation.

Should it be desired to disassemble the firearm, the barrel-cover 19 may first be removed, following which the stock may be detached from the remainder of the firearm mechanism. The unit comprising the receiver 16 and barrel 17 may now be separated from the frame 15 in any suitable manner, whereupon the exposed parts are now in condition to have the parts 20, 21, 22, 23 and other associated parts completely dismounted.

The next convenient step in the dismounting of the firearm parts would be to thrust forwardly upon the bracket 72 to disengage its coupling-finger 73 from the recess 74, whereupon the said bracket and the rear end of the said spring-guiding rod 71 may be swung laterally or downwardly, after which the said parts may be jointly removed from the receiver 16 in a rearward direction. The breech-closing spring 65 may now be withdrawn rearwardly from the cylinder-fitting 24 and from the interior of the piston 23 to thus unlock the forward end of the connecting-link 22 from the said piston.

The rear end of the coupling-lever 41 carried by the action-slide 21 may now be forced inwardly to disengage the coupling-nose 43 from the coupling-recess 44 in the rear coupling-lug 39 of the connecting-link 22. The rear end of the said connecting-link 22 may now be moved downwardly to remove its rear coupling-lug 39 from the recess 38 in the action-slide 21. Now by swinging the rear end of the connecting-link 22 outwardly and then upwardly to bring the said connecting-link into substantially the position in which it is shown in Fig. 11, the front coupling-lug 68 may be withdrawn outwardly through the clearance-slot 67 in the piston 23 and through the clearance-slot 58 in the cylinder 24. The connecting-link 22 now having been freed at both its respective opposite ends, may be removed from the structure, whereupon the piston 23 may be removed through the open rear end of the cylinder-fitting 24.

The breech-bolt 20 may now be disconnected

from the action-slide 21 by moving the said breech-bolt to the limit of its rearward movement, to thereby bring the relatively-slender forward end of the breech-bolt into the relatively large-dia-metered rear portion of the axial passage 28 in the receiver 16. The forward end of the breech-bolt may now be swung laterally to disengage its lug 39 from the cam-recess 34 in the action-slide 21, whereupon, if desired, the action-slide 21 may then be removed from the receiver 16 by sliding the said action-slide forwardly a sufficient distance to cause the rear ends of its guide-flanges 46 and 47 to clear the forward ends, respectively, of the guide-grooves 48 and 49 in the receiver 16.

The restoration of the parts to their assembled positions will be fully apparent from the foregoing description and the accompanying drawings.

The structure of Fig. 13

In Fig. 13, the parts correspond to those shown in the preceding figures and especially those shown in Figs. 4 and 11, and bear like reference characters with the exception of a connecting-link 78 and a piston 79. The piston 79 corresponds generally to the piston 23 before referred to and reciprocates in the same manner in the cylinder-fitting 24 and is provided with a rearwardly-opening axial socket 80 having a flat front wall 81. The piston 79 is formed with an upwardly-opening clearance-slot 82 corresponding to the clearance-slot 67 before described.

The connecting-link 78 corresponds to the connecting-link 22 before described, save that at its forward end it is provided with a front coupling-lug 83 having a dimension lengthwise of the firearm slightly less than the longitudinal dimension of the clearance-slot 82 in the piston 79. The said coupling lug 83 is provided with a forwardly-projecting coupling-finger 84 normally resting against the front wall 81 of the socket 80 in the piston 79. The said coupling-lug 83 is also formed with a rearwardly-projecting locking-finger 85 fitting within the forward end of the breech-closing spring 65.

As thus constructed, the forward end of the breech-closing spring 65 serves to positively prevent the radial outward movement of the front coupling-lug 83 of the connecting link 78, even though the said coupling-lug be moved rearwardly relative to the piston 79 sufficiently to bring the said coupling-lug into radial alignment with the clearance-slot 82 in the said piston.

By first rearwardly removing the breech-closing spring 65, the coupling-lug 83 of the connecting-link 78 may be brought into registry with the clearance-slot 82 in the piston 79, following which the said coupling-lug may be withdrawn radially outwardly through the said clearance-slot to totally free the forward end of the connecting-link 78 from the piston. The remaining parts may be disassembled and reassembled in the same manner as was made clear in connection with the description of the structure of Figs. 1 to 12 inclusive.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening piston-chamber communicating with the bore of the said barrel; a hollow piston reciprocating in the piston-chamber of the said cylinder and formed with a lateral opening extending between its hollow interior and its outer periphery; connecting-means operatively interconnecting the said piston and the said breech-bolt, including a link-like connecting-member extending lengthwise of the firearm-structure and having a coupling-portion extending laterally through the lateral opening in and into the hollow interior of the said piston to couple the connecting-member to the said piston; and breech-closing spring-means extending within the hollow piston and thrusting forwardly upon the laterally-extending coupling-portion of the said link-like connecting-member to cause the same to correspondingly thrust the said piston and the said breech-bolt.
2. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; connecting-means operatively interconnecting the said piston and the said breech-bolt and including a connecting-member extending lengthwise of the firearm-structure and having a coupling-portion extending laterally through the lateral passage and into the socket in the said piston, the said coupling-portion being provided with a coupling-finger extending therefrom in the socket in the said piston in a direction lengthwise thereof beyond the adjacent end of the lateral passage in the piston; and breech-closing spring-means thrusting forwardly upon the laterally-extending coupling-portion of the said connecting-member to cause the same to move the said piston and the said breech-bolt in a corresponding direction.
3. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; connecting-means operatively interconnecting the said piston and the said breech-bolt and including a connecting-member extending lengthwise of the firearm-structure and having a coupling-portion extending laterally through the lateral passage and into the socket in the said piston, the said coupling-portion being provided with a coupling-finger extending forwardly therefrom in the socket in the said piston and beyond the forward end of the lateral passage in the

said piston; and breech-closing spring-means thrusting forwardly on the connecting-member of the said connecting-means to cause the same to forwardly move the said piston and the said breech-bolt.

4. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; connecting-means operatively interconnecting the said piston and the said breech-bolt and including a connecting-member extending lengthwise of the firearm-structure and having a coupling-portion extending laterally through the lateral passage and into the socket in the said piston, the said coupling-portion being provided with a coupling-finger extending forwardly therefrom in the socket in the said piston and beyond the adjacent end of the lateral passage in the piston; and breech-closing spring-means engaging with and forwardly urging upon the laterally-extending coupling-portion of the said connecting-link to cause the latter to correspondingly urge the said action-slide and the said piston.

5. A gas-operated self-loading firearm-structure including in combination: a frame-structure; a breech-bolt movable in the said frame-structure; an action-slide slidable longitudinally on the said frame-structure and operatively connected to the said breech-bolt; a barrel projecting forwardly from the said frame-unit; a cylinder located adjacent the said barrel and having a rearwardly-opening piston-chamber communicating with the bore of the said barrel; a hollow piston reciprocating in the piston-chamber of the said cylinder and formed with a lateral opening extending between its hollow interior and its outer periphery; a connecting-link having a rear-portion detachably connected to the said action-slide and having a coupling-portion adjacent its forward end extending laterally through the lateral opening in and into the hollow interior of the said piston to couple the connecting-link to the said piston; and breech-closing spring-means extending within the hollow piston and thrusting forwardly upon the laterally-extending coupling-portion of the said connecting-link to cause the latter to correspondingly urge the said action-slide and the said piston.

6. A gas-operated self-loading firearm-structure including in combination: a frame-structure; a breech-bolt movable in the said frame-structure; an action-slide slidable longitudinally on the said frame-structure and operatively connected to the said breech-bolt; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; a connecting-link having a rear-portion detachably

connected to the said action-slide and having a coupling-portion adjacent its forward end extending laterally through the lateral passage and into the socket in the said piston to couple the said connecting-link to the said piston, the said coupling-portion being provided with a coupling-finger extending therefrom in the socket in the said piston in a direction lengthwise thereof beyond the adjacent end of the lateral passage in the piston; and breech-closing spring-means engaging with and forwardly urging upon the laterally-extending coupling-portion of the said connecting-link to cause the latter to correspondingly urge the said action-slide and the said piston.

7. A gas-operated self-loading firearm-structure including in combination: a frame-structure; a breech-bolt movable in the said frame-structure; an action-slide slidable longitudinally on the said frame-structure and operatively connected to the said breech-bolt; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; a connecting-link having a rear-portion detachably connected to the said action-slide and having a coupling-portion adjacent its forward end extending laterally through the lateral passage and into the socket in the said piston to couple the said connecting-link to the said piston, the said coupling-portion being provided with a coupling-finger extending forwardly therefrom in the socket in the said piston and beyond the forward end of the lateral passage in the said piston; and breech-closing spring-means extending forwardly into the socket in the said piston and thrusting forwardly upon the rear of the laterally-extending coupling-portion of the said connecting-link to cause the same to forwardly urge the said piston and the said action-slide.

8. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; connecting-means operatively interconnecting the said piston and the said breech-bolt and including a connecting-member extending lengthwise of the firearm-structure and having a coupling-portion extending laterally through the lateral passage in the said piston; and breech-closing spring-means extending forwardly into the open rear end of the socket in the said piston and into interlocking engagement with the laterally-extending coupling-portion of the connecting-member of the said connecting-means.

9. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening

piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; connecting-means operatively interconnecting the said piston and the said breech-bolt and including a connecting-member extending lengthwise of the firearm-structure and having a coupling-portion extending laterally through the lateral passage in the said piston, the said coupling-portion being provided with a rearwardly-extending locking-finger; and breech-closing spring-means extending forwardly through the open rear of the socket in the said piston and into locking engagement with the locking-finger of the coupling-portion of the said connecting-member.

10. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; connecting-means operatively interconnecting the said piston and the said breech-bolt and including a connecting-member extending lengthwise of the firearm-structure and having a coupling-portion extending laterally through the lateral passage in the said piston, the

5 said coupling-portion being provided with a rearwardly-extending locking-finger; and a helical breech-closing spring projecting forwardly into the socket in the said piston and having its forward portion encircling the locking-finger on the coupling-extension of the said connecting-member.

11. A gas-operated self-loading firearm-structure including in combination: a frame-structure; a breech-bolt movable in the said frame-structure; a barrel projecting forwardly from the said frame-structure; a cylinder located adjacent the said barrel and having a rearwardly-opening piston-chamber communicating with the bore of the said barrel; a piston reciprocating in the piston-chamber of the said cylinder and formed with a rearwardly-opening socket and with a lateral passage leading from the said socket intermediate the ends thereof to the outer periphery of the said piston; connecting-means operatively 10 interconnecting the said piston and the said breech-bolt and including a connecting-member extending lengthwise of the firearm-structure and having a coupling-portion extending laterally through the lateral passage and into the socket in the said piston, the said coupling-portion being provided with a coupling-finger extending forwardly therefrom in the socket in the said piston beyond the forward end of the lateral passage in the said piston, the said coupling-portion also 15 being provided with a locking-finger extending rearwardly in the socket of the said piston; and breech-closing spring-means projecting forwardly into the socket in the said piston and into locking engagement with the locking-finger of the coupling-portion of the said connecting-member.
